UNITED STATES PATENT OFFICE.

WILLIAM C. RATH, OF CINCINNATI, OHIO.

FISH-PLATE FOR RAILS.

1,076,233.

Specification of Letters Patent.

Patented Oct. 21, 1913.

Application filed July 15, 1912. Serial No. 709,374.

To all whom it may concern:

Be it known that I, WILLIAM C. RATH, a citizen of the United States, residing at Cincinnati, in the county of Hamilton and State of Ohio, have invented certain new and useful Improvements in Fish-Plates for Rails, of which the following is a specification.

My invention relates to self-locking fish-
10 plates for rails.

The object of my invention is to provide fish-plates for rails which are constructed so that two fish-plates substantially identical in construction will interlock with each 15 other upon and bind the meeting ends of the adjacent rails together without the use of bolts and nuts or other extraneous fastenings.

My invention consists of a fish-plate having interlocking lugs on the base thereof and an upright clamping portion at the side adapted to engage the side of the rails, and recesses at each end of said fish-plate adapted to register with like recesses on a 20 coöperating fish-plate when interlocked therewith, and an interlocking key to securely hold the fish-plate in interlocked position.

My invention further consists in the construction, combination and arrangement of parts as herein set forth and claimed.

In the accompanying drawing, which serves to illustrate my invention: Figure 1 is a perspective view showing part of the 35 fish-plate mounted on a rail; Fig. 2 is a perspective view of my improved fish-plate; Fig. 3 is a cross-section on a smaller scale taken on the line 3—3 of Fig. 1; Fig. 4 is a side elevation of my improved fish-plate; 40 and Fig. 5 is a perspective view of the interlocking key.

In the embodiment of my invention, as illustrated, and which shows a preferred construction, 1 represents a stock rail of the 45 ordinary type. The fish-plates 2 are constructed with a base portion 3 upon which the base of the rail is adapted to rest. The fish-plates 2 are also provided with vertical clamping portions 4 which are adapted to engage the side or web portion of the rail as shown in Fig. 1. These vertical clamping portions 4 are constructed to conform to the

outline of the rail, having a suitable recess 55 for the admission of the base 6 of the rail. The vertical clamping portions 4 may be counter-sunk as shown at 7 to allow a better and more uniform engagement of the fish-plate and the rail.

The base 3 of the fish-plate is provided with extending interlocking fingers or lugs 8. These interlocking fingers or lugs 8 which project from the base portion 3 have projections 8' thereon extending at right angles therefrom thereby forming spaces 9 in the interlocking lugs 8. These spaces 9 are formed just the proper size for the admission of the angular extension 8' on the fish-plate with which it is interlocked. Thus (as shown in Fig. 3) when two fish-plates are placed together, the space between the interlocking lugs is great enough to admit the interlocking fingers 8 and then when the fish-plates are moved longitudinally in opposite directions toward each other, the angular portions 8' on the fingers 8 enter the space 9, and thereby interlock the fish-plates together and prevent them from moving laterally, thereby clamping the rails together.

To prevent the fish-plates from moving longitudinally I provide recessed or cut away portions 11 and 12 at either end of the fish-plate. The cut away portion 12 has an extended lug 13 at the end thereof which is about half as thick as the thickness on the base 3 of the fish-plate, thereby leaving the upper half of the recess without obstruction. The recess 11 at the other end of the fish-plate is not provided with an extension 13 so that when another fish-plate is placed along side as that shown in Fig. 2, the recess 12 on that fish-plate will register with the recess 11 as shown in Fig. 1.

The recesses 11 and 12 are provided with 95 the tapering inclined sides 14 at the bottom thereof which are long enough to admit the interlocking key 15 shown in Fig. 5. When the two fish-plates are placed together as shown in Figs. 1 and 3 the interlocking key 100 15 is inserted into the recess 11 above the lug 13. It is then pushed into the recess to allow it to fall into engagement with the inclined sides 14 of the recesses 11 and 12. After the key has thereby been placed in the 105 recess 11, it is prevented from coming out

of engagement with the lug 13. When it is desired to remove the fish-plate, the key 15 must first be removed. In order to produce a more practical device for taking 5 apart or dismounting I provide an extension 16 on the interlocking key 15 which is adapted to fit adjacent the lug 13 on the fish-plate and thereby provide accessible means whereby the interlocking key 15 can 10 be easily lifted up when it is desired to remove the same.

It is readily seen that my improved fish-plate is reversible, as the same plate may be used for either side of the rail. It is also 15 seen that the lugs of interlocking fingers 8 may be constructed as strong as desired, and will absolutely clamp the rail securely without the use of bolts and nuts or other fastenings.

20 A certain amount of play may be allowed in the recesses 11 and 12, so that the key 15 will enter the recess 11, although the fish-plates due to the varying in thickness of the rail do not register absolutely. It will also 25 be noted that the entire sides of the angular extension 8' of the interlocking lugs are inclined so as to form an absolutely tight clamp for the rail when the fish-plates are driven together. The fish-plates are also 30 provided with a suitable number of notches or recesses 17 to allow the same to be fastened to the ties and prevent them from sliding longitudinally along the rails.

My invention has the advantage over fish-35 plates which are held in position by bolts and nuts of having no parts which will work loose or drop out of position and is, therefore, much more safe than prior constructions for the purpose.

40 Another advantage of my invention is that inasmuch as no holes are required in the rail or fish-plates, the same are much stronger and consequently are safer and more durable. In addition to this by dis-45 pensing with the holes I save the time and expense necessary to produce them.

An important advantage of my invention is that if a rail is broken requiring a new rail, or if it is desired to lay a temporary 50 track, the ends of the rails can be easily and quickly locked together in fixed alinement without requiring any holes, or bolts or nuts or other extraneous fastening means for this purpose.

55 Another advantage is that the interlocking fish-plates when secured together in interlocked position upon the abutting ends of adjacent rails permits of the usual contraction and expansion of the rails.

60 Certain modifications in my invention may be made without departing from the spirit or scope thereof, and I do not, therefore, wish to be confined to the exact details shown.

What I claim as new and desire to secure 65 by Letters Patent is:

1. A reversible fish-plate comprising a base portion and a vertical clamping portion, interlocking lugs extending from said base portion, an angular extension at the 70 end of each interlocking lug having an inclined surface at one side thereof, each base having a recess upon its inner edge between one end and the adjacent lug and each base having a recess upon its inner edge at its opposite end and provided with a lug, in combination with a coöperating fish-plate of like construction, said plates being adapted to engage the bottom and respective sides of the end portions of the abutting rails and to 75 interlock with each other and with said rails to clamp and hold said rails in proper and secure alinement with each other without the use of bolts, and a key adapted to enter each of said recesses horizontally and be 80 held therein by said lug, substantially as and for the purposes set forth.

2. A reversible fish-plate comprising a base portion and a vertical clamping portion, interlocking lugs extending from said 90 base portion, an angular extension at the end of each interlocking lug having an inclined surface on the inner side thereof, each base having a recess upon its inner edge between one end and the adjacent lug and 95 having the lower portion of its bottom inclined downwardly at an angle to the upper portion and each base having at its opposite end a similar recess with a lug at the end of the lower portion, in combination 100 with a coöperating fish-plate of like construction, said plates being adapted to engage the bottom and the respective sides of the end portions of the abutting rails and to interlock with each other and with said 105 rails in proper and secure alinement with each other and a longitudinally wedge-shaped key adapted to be inserted horizontally into the recesses formed by the coöperating members and held therein by said 110 lug, substantially as set forth and for the purposes specified.

3. A reversible fish-plate comprising a base portion and a vertical clamping portion, interlocking lugs extending from said 115 base portion, an angular extension at the end of each interlocking lug having an inclined surface on its inner side, each base having a recess upon its inner edge between one end and the adjacent lug and having the 120 lower portion of its bottom inclined downwardly at an angle to the upper portion, and each base having at its opposite end a similar recess with a lug at the end of the lower portion, in combination with a coöperating 125 fish-plate of like construction, said plates being adapted to engage the bottom and respective sides of the end portions of the

- abutting rails and to interlock with each other and with said rails to clamp and hold said rails in proper and secure alinement with each other, and a longitudinally wedge-shaped key adapted to be inserted horizontally into the recess formed by the coöperating members and held therein by said lug, said key having an extension adapted to fit adjacent said lug and thereby provide ac-

cessible means whereby said interlocking key can be easily lifted up when it is desired to remove the key, substantially as set forth and for the purposes specified.
